UNITED STATES PATENT OFFICE

95,000

DESIGN FOR A COMBINATION SEWING KIT, THREAD HOLDER, AND THREAD CUTTER

Laura S. Trumpler, Dayton, Ohio

Application June 7, 1934, Serial No. 52,096

Term of patent 7 years

To all whom it may concern:

Be it known that I, Laura S. Trumpler, a citizen of the United States, residing in the city of Dayton, in the county of Montgomery and State of Ohio, have invented a new, original, and ornamental Design for Combination Sewing Kit, Thread Holders, and Thread Cutters, of which the following is a specification, reference being had to the accompanying drawing, forming part hereof.

The figure is a perspective view of my combination sewing kit, thread holders and thread cutters, showing my new design.

I claim:

The ornamental design for a combination sewing kit, thread holders and thread cutters, as shown.

LAURA S. TRUMPLER.
